UNITED STATES PATENT OFFICE.

GEORGE A. LONG, OF HARTFORD, CONNECTICUT, ASSIGNOR TO THE GRAY TELEPHONE PAY STATION COMPANY, OF HARTFORD, CONNECTICUT, A CORPORATION OF CONNECTICUT.

HINGE.

SPECIFICATION forming part of Letters Patent No. 727,653, dated May 12, 1903.

Application filed June 7, 1901. Serial No. 63,548. (No model.)

To all whom it may concern:

Be it known that I, GEORGE A. LONG, a citizen of the United States, and a resident of Hartford, in the county of Hartford and State 5 of Connecticut, have invented certain new and useful Improvements in Hinges, of which the following is a full, clear, and exact description, whereby any one skilled in the art can make and use the same.

10 My invention relates to the class of gravity-operated hinges; and the object of my invention is to provide a hinge, more especially applicable for use in a telephone toll-collecting apparatus, which shall certainly insure the 15 automatic closing of the door of the case or box containing the telephone set, and, further, to provide a hinge for such use the ease of operation of which shall be such as to insure the automatic closing of the door when 20 it has been opened. A device by the use of which these objects may be obtained is illustrated in the accompanying drawings, in which—

Figure 1 is a view in front elevation of a 25 telephone - case embodying my invention. Fig. 2 is a view in elevation, on enlarged scale, of a portion of the door and case, showing my improved hinge. Fig. 3 is a like view, but showing the portion of the door raised 30 and hinge parts separated. Fig. 4 is a detail view in cross-section through the hinge. Fig. 5 is a view in central-vertical section through the hinge.

My invention is illustrated and described 35 herein in connection with a box or case within which a set of telephone instruments is inclosed and forming a street-telephone apparatus, the invention being especially adapted for use in connection with such an apparatus in which a coin is used for the purpose 40 of opening the door to gain access to the telephone and which is recovered after the door has been opened. In such an apparatus it is necessary that the door shall be readily 45 closed after the instrument has been used, and to this end it is essential that mechanism for closing the door shall be provided which shall be positive in its operation at all times and under any conditions of weather.

To accomplish this result, I have constructed 50 a hinge of the gravity-operated type and have so arranged and constructed the parts that they are not liable to become inoperative in use.

In the accompanying drawings, the letter 55 *a* denotes a post or standard supporting a box or case *b* of a street-telephone. This box or case is provided with a door *c*, having a handle *c'*, by means of which the door may be unlatched for the purpose of opening. 60 This door *c* is provided, preferably at the back and near each end, with the socket member *d* of the hinge in the form shown, this socket member being preferably cast integral with the door. A socket *d'* is formed in the 65 socket member, the bottom *d*² of the socket being formed on an incline or slope preferably extending in a straight line across the socket member.

A pintle member *e* is secured to the box or 70 case, in the form shown being cast integral therewith, this pintle member having a pin or pintle *e'* extending upward and of a diameter to so fit within the socket *d'* that the socket member *d* may be easily turned on the 75 pin and will at the same time completely inclose the working surfaces. The end *e*² of the pin is formed on a slope or incline corresponding to that of the bottom *d*² of the socket *d'* and preferably extending in a straight line across 80 the pin. This slope or incline on the bottom of the socket and end of the pin is so formed that the two surfaces lie flat against each other when the door is in the closed position.

It is important in providing an inclosing 85 casing for the purposes herein described that the door, as well as the main portion of the casing, have a considerable weight, and of course it is imperative that the door be let into and tightly fit within the casing in order 90 to exclude moisture, sleet, and dirt. It is also important that with such a heavy door it should swing to closed position with as little jar as possible and that a means be provided to prevent its rebounding. With the 95 construction of hinge herein described the end of the pintle and the bottom of the socket are in registering positions just as the door

reaches its closed position, and as the coacting surfaces are arranged in the same plane transverse to the axis of the pintle and socket a sort of stop is formed, which eases the closing of the door and tends to prevent its rebounding.

It will be noted from the above construction that all of the bearing parts are inclosed and there is little chance of dust or dirt gaining access to the inclined surface between the bottom of the socket and pin, so as to injuriously affect the working of the device. It will also be noted from the above construction that the means for automatically closing the door and for maintaining the engagement of the hinge members are included in the socket and pintle—that is, a separate pin is

not required for the latter-mentioned purpose.

What I claim as my invention, and desire to secure by Letters Patent, is—

In a hinge, in combination, a socket member having a socket with the bottom formed on an incline projecting in a straight line across the socket, and a pintle member having a pin adapted to fit said socket and with the end of the pin formed on an incline extending in a straight line across the pin and corresponding in shape to the bottom of the socket.

GEORGE A. LONG.
